CURTAIN SUPPORT

Daniel Fallone, Astoria, N. Y.

Application February 10, 1947, Serial No. 727,515

6 Claims. (Cl. 211—103)

1

This invention relates to fixtures for supporting curtains, or the like.

It is the primary aim and object of the present invention to provide a fixture by which a curtain may be raised or lowered through manipulation of a pull cord by a person standing on the floor, and which securely holds the curtain in its raised position, while requiring only a pull on the cord to release the curtain in its raised position for lowering the same.

It is another object of the present invention to provide a fixture of this type which is of simple and rugged construction, which readily lends itself to efficient and inexpensive mass production, and which may be used with curtain rods of any conventional type.

The above and other objects, features and advantages of the present invention will be more fully understood from the following description considered in connection with the accompanying illustrative drawings.

In the drawings:

Figure 1 is a perspective view of a curtain rod fixture embodying the present invention;

Figure 2 is an enlarged fragmentary section taken on the line 2—2 of Fig. 1;

Fig. 3 is an enlarged front elevation of a prominent part of the curtain fixture, as viewed in the direction of the arrow 3 in Fig. 1;

Fig. 4 is a fragmentary section taken substantially on the line 4—4 of Fig. 3; and

Fig. 5 is a view similar to Fig. 3, showing the fixture in a different operating condition, however.

Referring to the drawings, the reference numeral 10 designates the customary wooden framework for conventional windows 14 in a wall 12. Extending vertically along the side posts 16 of the framework 10 are guide rails or bars 18, respectively, having their rearwardly extending ends terminating in flattened mounting portions 20 which are secured to the adjacent side posts 16 by wood screws 22. The top mounting portions 20' of the guide rails 18 extend laterally outwardly thereof, and the holding screws 22' therethrough have forwardly extending shanks 24 (see also, Fig. 2) which terminate in eyes 26. Slidably on each guide rail 18 is a U-shaped bracket 28. Since these brackets 28 are identical, except that they are of reversed or left- and right-hand

construction, only one of these brackets will be described with particular reference to Figs. 2 and 3. As there shown, the right-hand bracket 28' has a preferably integral, lateral plate extension 30 which serves as a mounting for any conventional hanger 32 for a curtain rod end. In the present instance, the conventional type hanger shown in Figs. 3 and 4 is provided with a mounting plate 34 and a prong 36 which extends through holes 38 in the end of a curtain rod 40. The mounting plate 34 of the hanger 32 is customarily provided with drilled holes 42 for the reception of nails or screws with which to secure the hanger to a window frame. In the present instance, screws 44 are inserted in these holes 42 and extended through a hole 46 and an elongated slot 48, respectively, in the mounting plate 30 of the bracket 28', the threaded shanks 50 of the screws 44 receiving nuts 52 for the secure attachment of the hanger 32 to the plate extension 30 of the bracket 28'.

The long leg 54 of the bracket 28' has downwardly-bent ears 56 which straddle upwardly-turned ears 60 of a latch member 62, and a cotter pin 58, or the like, passes through the ears 56 and 60, thus pivotally mounting the latch member 62 on the bracket 28'. The latch member 62 is, in the raised position of the bracket 28' (Figs. 1 and 3), adapted to cooperate with a notch 64 in the adjacent guide rail 18 normally to prevent lowering of the bracket 28' and the end of the curtain rod 40 carried thereby.

Threaded through aligned holes in the latch member 62 and the bracket 28' is a pull cord 66 which is passed through the eye 26 of the adjacent mounting screw 22' in the fashion shown in Figs. 2 and 3 so as to be reversed in a downward direction, the adjacent end of this cord being knotted as at 68 so as to prevent its withdrawal from the latch member 62 when the cord is pulled. Surrounding the cord 66, and interposed between the latch member 62 and the leg 54 of the bracket 28', is a compression spring 70 which normally forces the latch member 62 into the latching position shown in Fig. 3. The cord 66 may be doubled-back as at 74 (Fig. 1) and passed through the eye 26 on the mounting screw 22', thence through the eye 26 on the opposite mounting screw 22' and through a hole 76 in the other bracket 28" into anchored relation

with the pivoted latch member 62 on the latter. The lower end of the pull cord 66 may conveniently be wound around a peg 78 in one of the side posts 16 of the framework 10.

The curtain rod 40, which may either be a single rod as shown, or may be of the well-known extensible type, has mounted thereon any suitable curtain 80 shown in dot-and-dash lines in Fig. 1. The curtain fixture, which is comprised of the brackets 28, hangers 32 and curtain rod 40, is held in the normal raised position shown in Figs. 1 and 3 by means of the latched members 62 on the brackets 28. If it is desired to lower the curtain fixture, the cord 66 is released from the peg 78 and pulled sufficiently to rock the latch members 62 out of their respective notches 64 in the adjacent guide rails 18 (Fig. 5) against the tendency of their associated springs 70 to hold them in latched position. The latch members 62 will thus be rocked out of latching position because their associated springs 70 will yield under the load then imposed on them, namely, the curtain 80, curtain rod 40, hangers 32 and brackets 28. After pulling the cord 66 for the release of the latch members 62 from their respective notches 64 in the adjacent guide rails 18, the curtain fixture is permitted to descend on the guide rails 18 under the control of the pull cord 66. In order to raise the curtain fixture to its normal position (Fig. 1), the cord 66 is pulled until the latch members 62 on the brackets 28 have passed above the notches 64 in the adjacent guide rails 18, i. e. when the brackets 28 have reached the upper ends of their respective guide rails, whereupon the cord 66 is suddenly slackened, with the result that the brackets 28 of the curtain fixture will descend on their respective guide rail 18 until the latch members 62 align with, and snap into, the adjacent notches 64.

The guide rails 18 are preferably square in cross section, and the brackets 28 are provided with correspondingly shaped holes by which they are guided on the rails 18. By this expediency, the brackets 28 are prevented from turning on their respective guide rails 18 and the curtain fixture is in consequence thereof rendered most stable in use.

While only one form of conventional hanger 32 is shown adapted for attachment to the brackets 28, it is to be understood that other known types of curtain rod hangers may be used in lieu of that shown, so long as they have drilled mounting plates which are adapted for quick mounting on the brackets 28 in the manner explained.

The guide rails 18 may also be attached to the side posts 16 of the framework in the reverse order in which they are shown in Fig. 1, in which case the hung curtain extends over these guide rails as well as over the adjacent brackets 28 and effectively hides them from view.

While I have shown and described the preferred embodiment of my invention, it will be understood that various changes may be made in the present invention without departing from the underlying idea or principles of the invention within the scope of the appended claims.

Having thus described my invention, what I claim and desire to secure by Letters Patent, is:

1. A curtain rod fixture, comprising guides, each guide having a shoulder and mounting portions for vertical attachment of said guide to an upright support, a bracket slidably mounted on each of said guides and having a mounting for a curtain rod, and a pivoted detent on each of said brackets spring-urged into latching engagement

with the shoulder on said guide in the raised position of said bracket, said detent having provision for securing thereto a cord remotely from the pivot axis of said detent.

5 2. A curtain rod fixture, comprising guides, each guide having a shoulder and mounting portions for vertical attachment of said guide to an upright support, a bracket slidably mounted on each of said guides and having a mounting for a curtain rod, and a pivoted detent on each of said brackets spring-urged into latching engagement with the shoulder on said guide in the raised position of said bracket, said detent having provision for securing thereto one end of a cord such that a pull thereon upwardly away from said detent will rock the latter out of latching position and raise said bracket on said guide, respectively.

10 3. A curtain rod fixture, comprising guides, each guide having a shoulder, and mounting portions for vertical attachment of said guide to an upright support, a bracket slidably mounted on each of said guides and having a mounting for a curtain rod, a pivoted detent on each of said brackets spring-urged into latching engagement with the shoulder on said guide in the raised position of said bracket, said detent having provision for securing thereto one end of a cord such that a pull thereon upwardly away from said detent will rock the latter out of latching position and raise said bracket on said guide, respectively, and an eye at the top of each mounted guide through which to pass the respective cord.

15 4. A curtain rod fixture, comprising guides, each guide having a shoulder and mounting portions for vertical attachment of said guide to an upright support, a bracket slidably mounted on each of said guides and having a mounting for a curtain rod and a horizontally extending lug, a pivoted detent on each of said brackets underneath the lug thereof, and a helical compression spring interposed between the lug and detent of each bracket to urge said detent into latching engagement with the shoulder on the associated guide in the raised position of said bracket on said guide, each detent having means for securing thereto one end of a cord whereby a pull thereon upwardly away from said detent effects rocking of the latter out of latching position and raising of the corresponding bracket on its guide, respectively, each lug having a hole through which to extend the corresponding cord after the same is passed axially through the corresponding spring to keep the latter in place.

20 5. A curtain rod fixture, comprising guides, each guide having a shoulder and mounting portions for vertical attachment of said guide to an upright support, a bracket slidably mounted on each of said guides and having a mounting for a curtain rod and a horizontally extending lug, a pivoted detent on each of said brackets underneath the lug, thereof, a helical compression spring interposed between the lug and detent of each bracket to urge said detent into latching engagement with the shoulder on the associated guide in the raised position of said bracket on said guide, each detent having means for securing thereto one end of a cord whereby a pull thereon upwardly away from said detent effects rocking of the latter out of latching position and raising of the corresponding bracket on its guide, respectively, each lug having a hole through which to extend the corresponding cord after the same is passed axially through the corresponding spring to keep the latter in place, and an eye at the top

of each mounted guide through which to pass the corresponding cord.

6. A curtain rod fixture, comprising a guide having an apertured end, means for mounting the ends of said guide on an upright support, said means including a member having a threaded shank adapted to be passed through said apertured guide end and threaded into said support, a cap from which said shank projects, and an eye projecting from said cap oppositely to said shank through which a pull cord may slide, and a mounting bracket for a curtain rod slidably mounted on said guide and having an attachment for an end of a pull cord.
